UNITED STATES PATENT OFFICE.

HENRY STOFFEL, OF TULSA, OKLAHOMA.

FLUSHING-TANK.

1,230,053.

Specification of Letters Patent. Patented June 12, 1917.

Application filed March 12, 1917. Serial No. 154,199.

To all whom it may concern:

Be it known that I, HENRY STOFFEL, a citizen of the United States, residing at Tulsa, in the county of Tulsa and State of Oklahoma, have invented a new and useful Flushing-Tank, of which the following is a specification.

The present invention appertains to flushing tanks, and aims to provide a novel and 10 improved device of that character.

It is the object of the invention to provide a flushing tank provided therein with a tilting receptacle for receiving the water and holding it, said receptacle being tilted to 15 dump the water into the tank for the flushing operation, the device eliminating the use of a float valve for holding the water in the tank as usual, and embodying novel features of construction to enhance the utility 20 and efficiency thereof.

It is also the object of the invention to provide a novel assemblage of the component elements, and to provide means whereby the receptacle or inner tank is prevented 25 from scooping up the water after the receptacle is tilted, thereby assuring of the full discharge of water from the tank.

With the foregoing and other objects in view which will appear as the description 30 proceeds, the invention resides in the combination and arrangement of parts and in the details of construction hereinafter described and claimed, it being understood that changes in the precise embodiment of 35 the invention herein disclosed, can be made within the scope of what is claimed, without departing from the spirit of the invention.

The invention is illustrated in the accompanying drawings, wherein:—

Figure 1 is a side elevation of the tank.

Fig. 2 is a vertical median section, portions being broken away and portions being shown in elevation.

Fig. 3 is a vertical section showing the receptacle or inner tank tilted.

Fig. 4 is a horizontal section taken on the line 4—4 of Fig. 2.

Fig. 5 is a vertical section taken on the 50 line 5—5 of Fig. 1.

In carrying out the invention, there is provided a circular or cylindrical tank disposed in a vertical plane with its axis horizontal and embodying the lower and upper 55 semi-circular sections 1 and 2, the upper section 2 being fitted upon the lower section,

and the lower section 1 having a lower outlet 3. The tank can be constructed of sheet metal, cast iron or other suitable material, and may be suitably finished upon the interior. Hung for rocking movement within the tank is a semi-circular receptacle or inner tank 4 constructed of sheet metal or other suitable material, and preferably disposed concentric within the tank with its curved bottom and end walls spaced from the periphery of the tank. As a means for mounting the receptacle within the tank, a bearing plate 5 is disposed at the inner side of one flat side wall of the lower tank section 1 and has offset edge portions 6 riveted or otherwise secured to said side wall. The plate 5 has an upwardly opening notch or seat 7, and a plate 8 is secured to the corresponding flat side wall of the receptacle 4 and has an outstanding trunnion 9 seated in the notch 7, and provided with a head 10 engaging behind the plate 5 to lock the trunnion to the bearing plate. An outstanding trunnion 11 is attached in any suitable manner to the opposite flat side wall of the receptacle 4, the trunnions 9 and 11 being located adjacent to the upper edges of the receptacle intermediate the ends thereof. The trunnion 11 seats in an upwardly opening notch or seat 13 of a plate 12 secured to the outer surface of the other flat side wall of the lower tank section 1, said side wall also having an upwardly opening slot or notch 14 for receiving the trunnion 11. The receptacle 4 is thus hung from the trunnions 9 and 11 and normally tends to swing to a depending position. A radial lever or handle 15 is secured to the trunnion 11 for tilting the receptacle, and can project in any desired direction. Stop lugs 16 are carried by the plate 12 for limiting the movement of the lever 15. A chain or other flexible element can be connected to the lever 15 for operating the device when it is elevated or 90 out of reach. When the upper tank section or cap 2 is removed, the receptacle can be readily lifted out of the lower tank section, since the trunnions 9 and 11 are readily removed upwardly from their bearing plates 105 5 and 12.

The water is delivered into the receptacle from a horizontal tubular valve casing 17 having one end engaged outwardly through one end of the lower tank section 1, and to 110 which end of the casing the water supply pipe 18 is connected. The valve casing 17

has a lower discharge nozzle 19 extending inwardly and downwardly and overhanging the corresponding end of the receptacle when it is in depending position as seen in Fig. 2, 5 the corresponding end wall of the receptacle having a recess or opening 20 for accommodating the nozzle 19 and valve casing 17. The valve casing 17 has a valve seat 21 between its inward end and the nozzle 19, and 10 a plunger 22 is slideable within the valve casing at that side of the nozzle passage opposite the valve seat 21. The plunger 22 carries a valve stem 23 which projects outwardly through the valve seat 21, and which 15 carries the valve 24 that is seatable against the seat 21 for shutting off the flow of water into the receptacle. The plunger 22 has a slot 25 extending laterally therethrough and the valve casing 17 has a longitudinal slot 20 26 above the slot 25, a lever 27 extending upwardly through the slots 25 and 26 and having its lower end fulcrumed or pivoted, as at 28, to the lower portion of the valve casing below the plunger and above the nozzle 19. The valve casing 17 has an upwardly 25 extending bracket 29 within the tank to which a lever 30 is pivoted between its ends, and the lower arm of the lever 30 is connected by a link 31 with the upper end of 30 the lever 27. The upper arm of the lever 30 has a circular notched head 32 carrying a clamping element 33 through which a rod 34 is slideable, and the clamping element 33 is adapted to clamp the rod 34 at different 35 angular positions against the head 32. The rod 34 extends into the receptacle and is provided at its ends with a suitable float 35 movable within the receptacle.

A suitable float 36 is attached to the acute 40 angle wall of the receptacle 4 adjacent to that end thereof which moves under the valve casing 17 and which moves downwardly when the receptacle is tilted.

The operation is as follows: The receptacle 45 is normally in depending position when filled with water, and when the lever 15 or other operating member is swung properly, this will tilt the receptacle, as seen in Fig. 3, whereby the water will flow therefrom into the lower portion of the tank, and then flow 50 with a gushing action through the outlet 3. Due to the presence of the float 36 within the depressed end of the receptacle, said float in tending to rise in the water will hold the receptacle tilted, since the float 36 is 55 moved downwardly below and past the vertical plane of the trunnions or pivots of the receptacle. This prevents the receptacle, when released, from swinging back to depending 60 position and scooping up the greater portion of the water. Consequently, the float 36 will hold the receptacle in tilted

position, and permit all of the water to be discharged. The float 36 will not permit the receptacle to swing back to depending 65 position, until the water level in the tank is lowered below the float 36 and the depressed end of the receptacle. After the water has been discharged sufficiently from the tank, the weight of the receptacle 4 will swing it 70 back to depending position. The rod 34 swings downwardly within the receptacle after the water is discharged, due to the lowering of the float 35, and this will swing the lever 30 to the position seen in Fig. 2, where- 75 by the link 31 is pulled to swing the lever 27 so as to force the plunger 22 and valve 24 against water pressure. The valve is thus opened, so that the water flows past the seat 21 and through the nozzle 19 into the receptacle 4, and as said receptacle is filled, the float 35 is raised. This will swing the rod 34 and lever 30, whereby the link 31 pushes the lever 27 to slide the plunger 22 with it and gradually close the valve 24. Said valve 80 is closed when the receptacle is filled. It will be noted that the float 36 being adjacent to the end of the receptacle which is depressed, will when the receptacle is in depending position, and filled with water, tend 85 to hold the corresponding end of the receptacle up, to avoid accidental tilting or swinging thereof. The receptacle holds the water without the necessity of using a float valve, as usual, for closing the outlet 3. 90

An adjustable weight 50 is mounted on the rod 34, whereby when the water level is lowered, said weight will swing the rod downwardly by gravity, to open the valve against the water pressure.

Having thus described the invention, what is claimed as new is:—

1. A device of the character described embodying a tank having a lower outlet, a tilt-able receptacle within the tank, and a float 105 carried by the receptacle in position to be moved below the pivot of the receptacle and past the vertical plane thereof when the receptacle is tilted, for holding it tilted until the water flows therefrom.

2. A device of the character described embodying a tank having a lower outlet, a tilt-able receptacle within the tank having a de- 110 pressible end, and a float within the receptacle attached thereto adjacent to said end and movable downwardly past the vertical plane of the pivot of the receptacle.

In testimony that I claim the foregoing as my own, I have hereto affixed my signature in the presence of two witnesses.

HENRY STOFFEL.
